LETTER CARRIER'S CART

Gilbert J. Savoy, 1239 Collyer St., Longmont, Colo.

Filed Aug. 27, 1962, Ser. No. 71,454

Term of patent 14 years

(Cl. D14—3)

FIG. 4

FIG. 1 is a front elevational view of a letter carrier's cart, showing my new design;
FIG. 2 is a left side elevational view thereof;
FIG. 3 is a rear elevational view thereof; and
FIG. 4 is a perspective view thereof.
The drawing is lined to represent color contrast.

I claim:
The ornamental design for a letter carrier's cart, as shown and described.
